US00D950719S

(12) **United States Design Patent** (10) **Patent No.:** **US D950,719 S**
(45) **Date of Patent:** **** May 3, 2022**

(54) **TISSUE LIGATION DEVICE**

(71) Applicant: **Boston Scientific Scimed, Inc.**, Maple Grove, MN (US)

(72) Inventors: **Kyle P. Moore**, Alpharetta, GA (US); **William D. Webb, II**, San Francisco, CA (US); **Quinn Fitzgerald**, San Francisco, CA (US); **Julian Gregory**, San Francisco, CA (US)

(73) Assignee: **Boston Scientific Scimed, Inc.**, Maple Grove, MN (US)

(**) Term: **15 Years**

(21) Appl. No.: **29/727,655**

(22) Filed: **Mar. 12, 2020**

(51) LOC (13) Cl. **24-02**

(52) U.S. Cl.

USPC **D24/130**

(57) **CLAIM**

The ornamental design for a tissue ligation device, as shown and described.

DESCRIPTION

FIG. 1 is an isometric view of a tissue ligation device; FIG. 2 is a first side view of the design of FIG. 1; FIG. 3 is a second side view of the design of FIG. 1; FIG. 4 is a top view of the design of FIG. 1; FIG. 5 is a bottom view of the design of FIG. 1; FIG. 6 is a first end view of the design of FIG. 1; FIG. 7 is a second end view of the design of FIG. 1; and, FIG. 8 is an isometric exploded view of the design of FIG. 1.

The broken lines in the drawings illustrate portions of the tissue ligation device which forms no part of the claimed design.

1 Claim, 7 Drawing Sheets
